THERMOSTAT

Robert J. Parsons, Schenectady, N. Y., assignor to
 Consolidated Car-Heating Company, Inc., Albany, N. Y., a corporation of New York

Application September 4, 1934, Serial No. 742,546

6 Claims. (Cl. 200—140)

This invention relates to thermostats, more especially to a thermostat embodying a temperature responsive fluid, and particularly to a thermostat having an element of the bellows type responsive to changes in pressure.

A principal object of this invention is to produce a device of the type specified which will be compact, easy to adjust, simple and inexpensive to manufacture, particularly free from a tendency to get out of order, very sensitive in its response to changes of temperature, and certain and powerful in its action.

Other objects and advantages will appear as the description of the particular embodiment selected to illustrate the invention progresses, and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

Figure 1 is a vertical sectional view of a panel with a thermostat of applicant's invention in place thereon, parts being shown in elevation; Fig. 2 is a cross-sectional view of the device on the plane indicated by the line II—II of Fig. 1, (or Fig. 3) viewed in the direction of the arrows at the ends of the line; Fig. 3 is a fragmentary, detail view in vertical section of the device on the plane indicated by the line III—III of Fig. 1, viewed in the direction of the arrows at the ends of the line; Fig. 4 is a vertical section of the device on the plane indicated by the line IV—IV of Fig. 2, viewed in the direction indicated by the arrows at the ends of the line.

In the figures, numeral 1 designates a panel or mounting member upon which applicant's device may be positioned. This panel may be made of any suitable material and in the instance illustrated is made of insulating material, as is usual.

Attached to the panel 1, preferably by means of bolts, as 2, is a collar 3, having a flange 4 with apertures 5 to receive the bolts 2. Within the bore 6 of this collar is fitted an elongated tube 7, of suitable material, preferably metal, as in the instance illustrated, and having a lower closed end 8, the upper end of the tube having an open mouth 9 surrounded by an integral lip or flange 10, of suitable size to fit snugly within a recess 11 provided for that purpose in the upper face of the flange 4.

Within the tube 7 is positioned an elongated

collapsible bellows element 12, which is assembled with the tube 7 and collar 3 by means of a flange 13 which, as shown, is substantially of the same dimensions as that of the flange 4 and extends over the lip or flange 10 of the tube, in contact therewith, so that when the bolts 2 are tightened, a fluid tight joint is formed between the mouth flanges 10 and 13. A gasket 14 is preferably provided between the flange 13 and the panel 1, to obviate any cutting action upon the flange 13 by the contiguous edge 15 of an aperture 16, provided in the panel for a purpose to be described.

The bellows structure or element 12 is preferably substantially co-extensive in length, in its expanded state, as shown, with the surrounding tube 7 and is of suitable diameter to nearly fill the chamber 17 formed between the inner walls 18 of the tube and the corrugated exterior walls 19 of the bellows.

This chamber is adapted and intended to receive a suitable temperature responsive fluid (not shown) such as glycerine as usual, and the chamber serves as a fluid-pressure chamber, any rise in the temperature of the enclosed fluid exerting a collapsing force lengthwise upon the bellows.

Within the bellows 12 is provided a rod 20 the inner end 21 of which is positioned in the path of the axially moving bottom of the bellows, which may be desirably formed with a member 22 which serves as a closure and also as a reinforcement for the inner end of the bellows, and as an abutment to resist the wear exerted by the inner end 21 of the rod, the latter being preferably rounded, as illustrated, to reduce such wear.

The rod 20 is of sufficient length to project, at its upper end, 23, beyond the mouth of the bellows, through an aperture 24 in the gasket 14, and extends up through the panel aperture 16, which is provided to accommodate such projection of the rod.

The tube 7, bellows element 12, and rod 20, with their associated mounting and assembling parts above described, act, in cooperation with the temperature responsive fluid in the fluid pressure chamber 17, as a thermostat of sturdy construction, very sensitive to changes in the temperature of any environment in which the tube 7 may be placed, which changes in temperature are quickly conducted to the fluid by the walls of the tube 7 and are there converted into changes of pressure to which the bellows responds immediately, the collapsing movement lengthwise of the bellows being transmitted to the rod 20, which is

moved bodily along its major axis, and this movement may be translated usefully by suitable means provided in the path of the upper projecting end 23 of the rod.

5 This arrangement of thermostat at one side of the panel lends itself to the provision on the other side of any suitable device intended to be operated by the thermostat, and it will be noted that the thermostat constitutes a self-contained, unitary 10 structure, capable of combination with a variety of different devices, as well as interchangeably with any of a series of devices of similar, standard structure, designed for such interchangeable use.

15 As an illustrative example of a useful application of the thermostat above described, I have shown in the drawing an electrical-circuit-controlling switch mounted upon the panel 1, and adapted to be opened by upward movement of the rod 20 upon a rise in temperature of the fluid in 20 chamber 17, accompanied by collapsing reponse of the bellows 12.

The switch structure comprises a metal frame having a base 24' secured to the panel by the threaded end 25 of one of the bolts 2, which is 25 screwed into a threaded aperture 26 of the base 24', and the base is similarly secured by other bolts 27 passing through the panel 1 and screwed into suitable portions of the base, which is L-shaped, as best seen in Fig. 4.

30 From one leg of the L-shaped base extends upward a forked bracket 28, the arms of which are traversed by a pin 29 secured in place by a cotter pin 30 and which serves as a pivot for a switch lever 31, the latter having a spring contact finger 32 with a button 33 adapted to make and break electrical contact with a cooperating contact stud 34 mounted on a post 35 which has a foot 36 secured to panel 1 by screws 37 passing through the panel from beneath. The base has a terminal binding post or screw 38 to which can be connected one conductor C of the electrical circuit to be controlled by the switch. A suitable terminal plate 40 facilitates this connection and another conductor C' of the electrical circuit is 45 shown as connected by a similar plate 40 and binding screw 42 to a lug 43 formed integrally with the base 24'. The base and all metal parts associated with it, including the various elements of the thermostat, are therefore grounded to one 50 conductor of the circuit. The first named conductor C, and terminal 36 are insulated, by the material of panel 1, from the base, etc., when the contacts 33 and 34 are separated by upward swinging movement of the finger 32 into the 55 dotted line position shown in Fig. 4.

The switch lever 31 and finger 32 are normally biased toward this circuit breaking position by the coil spring 44, which is held under compression between the base 24' and switch lever 31, being 60 fitted at its lower end in a base socket 45 and at its upper end upon a lug 46 depending from the lower face of lever 31. A push-button 47 of insulating material, mounted on an offset lug 48 of the lever 31, may be used to depress the lever 31 and finger 32 manually to complete the electrical circuit at 33, 34.

In the present instance, as already indicated, the closed circuit position is the normal position of the switch, which is designed to be opened by 70 action of the thermostat, but this, of course, is merely illustrative of one use of the thermostat.

In pursuance of this intended use of the invention illustrated, provision is made of a means to hold the switch lever in its depressed closed circuit position shown in full lines throughout the 75

figures, the illustrated means taking the form of a latch 49 fast upon a rock shaft 50 which is mounted rotatively in uprights 51 and 52 of the frame and around which is coiled a spring 53 which biases the shaft 50 in a counter-clockwise direction (see Figs. 1 and 2). This causes an upright hook 54, forming part of the latch, to engage a lug 55, offset from the switch lever 31, and to hold the lever 31 and finger 32 in their depressed full line position, to maintain the contacts 33 and 34 in their circuit-closing position.

10 The latch 49 is formed with an integral finger 56, which extends into proximity to the path of the rod 20 and is adapted to be engaged with a collar 57 secured upon the rod and which is adapted to turn the latch in clockwise direction, against the bias of coil spring 53, and thus release the switch lever 31, when the rod 20 is moved upwardly by collapsing action of the bellows 12, upon a sufficient rise in temperature of the fluid 20 in chamber 17, and a corresponding development of pressure adapted to collapse the bellows.

When the temperature of the fluid in chamber 17 falls, and the collapsing pressure on bellows 12 therefore fails, there is a natural tendency of the 25 bellows structure to assume its extended position, owing to the resiliency of the corrugated walls if, as usual, the bellows is made of a resilient metal. The action of coil spring 53 thereupon tends to depress the arm 56 and restore the lock 54 30 to its upright position, ready to engage and hold the switch lever 31 and spring finger 32 in full line position, maintaining the contacts 33, 34 in closed circuit position when the push button 47 35 has been operated manually for this purpose.

While the weight of rod 20, and the downward bias of arm 56, under the above described action of spring 53, is ordinarily sufficient to cause the rod 20 to follow the bottom 22 of bellows 12 as the latter expands, I prefer to provide an auxiliary 40 means tending to bias the rod 20 downward, and to aid in expanding the bellows 12, and for this purpose have shown a coil-spring 58, mounted between an overhead bracket 59 of the frame upright 52 and the rod collar 57, which latter has 45 an upright annular boss 60 within which the lower end of spring 58 is seated, surrounding the upper end 23 of the rod. This end may desirably be threaded to afford a seat on which the collar 57 may be screwed to adjust the same and thereby 50 to regulate the tension of spring 58. A set screw 61 serves to hold the collar 57 in adjusted position.

The bracket 59 may be recessed, as at 62, to seat the upper end of the spring 58, and may be 55 strengthened by a web 63. It is also provided with a pin 64, to limit the upward swing of the switch lever 31 and spring finger 32. This finger is preferably fastened securely to the arm, as by rivets 65, and in general provision is made for securing 60 the parts of the switch in rigidly assembled relation wherever that is desirable. The bolts 2 are of sturdy structure, and the left-hand bolt is provided with a strong retaining nut 66, with washers 67 adapted to protect the insulating material of 65 which panel 1 is composed.

It should be noted also that the various working parts are biased independently by the action of individual springs, so that there is no possibility of lost motion in any position, whether operative or inoperative. This aids to promote sensitive, rapid and sure response to operative impulses, and prevents rattling of the parts when the device is associated with a vibrating structure, or one exposed to shocks in use.

Although I have particularly described one particular physical embodiment and explained the operation, construction and principle thereof, nevertheless, I desire to have it understood that 5 the form selected is merely illustrative but does not exhaust the possible physical embodiments of the idea of means underlying my invention.

What I claim as new and desire to secure by Letters Patent of the United States, is:

- 10 1. In a thermostat, in combination: a thin-walled metal tube having a closed end and an open end with a radial peripheral flange; a tubular, bellows-type pressure-responsive structure within said tube, having a closed inner end and an open end with a radial peripheral flange superimposed upon said tube flange; a separately formed collar of heavier material, having a hollow boss within which the open ends of said tubular members are disposed and having a broad flange upon which 15 said tubular flange and bellows flange are superimposed in the order named; means to secure said flanges together in fluid-tight assemblage, whereby a fluid pressure chamber is formed between the inner walls of said tube and the exterior walls of said bellows, said chamber being adapted to receive a temperature responsive fluid which serves to exert a lengthwise acting collapsing force upon said bellows structure when the temperature of said fluid rises; and a rod 20 within said bellows, having one end positioned in the path of movement of the closed inner end of the bellows and having its other end projecting beyond the flanged mouths of the tube and bellows. 25
2. In a thermostat, in combination: a thin-walled metal tube having a closed and an open end with a peripheral flange; a tubular, bellows-type, pressure responsive structure within said tube, having a closed inner end and an open end with a peripheral flange superimposed upon said tube flange; a separately formed collar of heavier material, having a hollow boss within which the open ends of said tubular members are disposed and having a broad flange upon which 30 said tubular flange and bellows flange are superimposed in the order named; means to secure said flanges together in fluid tight assemblage, whereby a fluid pressure chamber is formed between the inner walls of said tube and the exterior walls of 35 said bellows, said chamber being adapted to receive a temperature responsive fluid which serves to exert a lengthwise acting collapsing force upon said bellows structure when the temperature of said fluid rises; and a rod within said bellows, having one end positioned in the path of movement of the closed inner end of the bellows and having its other end projecting beyond the flanged mouths of the tube and bellows; said device being further characterized by a supporting structure upon which said device is mounted, a coil spring on said rod and bearing at one end against said supporting structure, being adapted to bias said rod in opposition to said collapsing force, said device being also characterized by a collar adjustable lengthwise on said rod to serve as a movable abutment for the other end of said spring, thereby to vary the strength of said bias. 40
3. In a thermostat, in combination: a thin-walled metal tube having a closed end and an open end with a peripheral flange; a tubular, bellows-type, pressure-responsive structure within said tube, having a closed inner end and an open end with a peripheral flange superimposed upon said tube flange; a separately formed collar of heavier material, having a hollow boss within which the open ends of said tubular members are disposed and having a broad flange upon which 45 said tubular flange and bellows flange are superimposed in the order named; means to secure said flanges together in fluid-tight assemblage, whereby a fluid pressure chamber is formed between the inner walls of said tube and the exterior walls of said bellows, said chamber being adapted to receive a temperature responsive fluid which serves to exert a lengthwise acting collapsing force upon said bellows structure when the temperature of said fluid rises; and a rod within said bellows, having one end positioned in the path of movement of the closed inner end of the bellows and having its other end projecting beyond the flanged mouths of the tube and bellows; said device being further characterized by a supporting structure upon which said device is mounted, and also characterized by an electrical circuit controlling switch having an electrical contact member spring-biased to open position, and a latch spring-biased independently to a position for holding said contact member normally in 50 circuit closing position, said parts being respectively mounted on said support with a part of said latch in position to be tripped mechanically by said rod when moved by the bellows, operated by thermo-responsive conditioning of the fluid in 55 the fluid pressure chamber. 60
4. In a thermostat, in combination: an apertured supporting panel; a thermostat mounted thereon, including a temperature-responsive fluid-pressure chamber with an enclosed pressure-responsive bellows structure and an axially disposed rod within said bellows, said thermostat being chiefly positioned upon one side of said panel and said rod being movable through the panel aperture by pressure-induced 65
5. A thermostatic device comprising, in combination: an apertured supporting panel; a thermostat mounted thereon, including a temperature-responsive fluid-pressure chamber with an 70 enclosed pressure-responsive bellows structure and an axially disposed rod within said bellows, said thermostat being chiefly positioned upon one side of said panel and said rod being movable through the panel aperture by pressure-induced 75

collapse of said bellows, and a means upon the other side of said panel for translating usefully said movement of said rod; said translating means including an adjustable collar upon said rod, a frame mounted upon said panel opposite said panel aperture, an electrical switch contact-lever and a restraining-latch for said lever, both mounted pivotally upon said frame; and a series of springs respectively seated upon said frame and biasing said rod, contact lever and latch independently, one spring tending to move the latch into position to hold the contact lever in closed position, another spring tending to throw the switch lever to open the circuit when the latch is thrown off by the rod, and a third spring acting to move the rod in opposition to collapsing movement of the bellows.

6. A thermostatic device comprising, in combination: an apertured supporting panel; a thermostat mounted thereon, including a temperature-responsive fluid-pressure chamber with an enclosed pressure responsive bellows and an axially disposed rod within said bellows, said thermo-

stat being chiefly positioned upon one side of said panel, and said rod being movable through the panel aperture by pressure-induced collapse of said bellows, and a means upon the other side of said panel for translating usefully said movement of said rod; said translating means including an adjustable collar upon said rod, a frame mounted upon said panel opposite said panel aperture, an electrical switch contact-lever and a restraining latch for said lever, both mounted pivotally upon said frame; and a series of springs respectively seated upon said frame and biasing said rod, contact lever and latch independently, one spring tending to move the latch into position to hold the contact lever in closed position, another spring tending to throw the switch lever to open the circuit when the latch is thrown off by the rod, and a third spring acting to move the rod in opposition to collapsing movement of the bellows; and a push button for manually closing said switch and concurrently resetting said latch in its restraining position.

ROBERT J. PARSONS.
